Claims priority, application France, June 29, 1960, 831,513

13 Claims. (Cl. 340—364)

Coding switches have the object of making it possible to code a number of analogue quantities in the course of each of their cycles.

The coding switch comprises a mechanical switch having a control arm successively actuating the contacts of a number of switch housings in the course of a complete revolution made in a period of T seconds. The contacts, N in number, are each closed for a period τ , the change of connection by the arm of the switch from one position to another taking place at regular intervals by means of a rapidly operating mechanism controlled by the position of a shaft driven by a motor. Such a mechanism is described in U.S. Patent 3,132,537, dated May 12, 1964. At each of the positions are coded a number n of magnitudes, so that during the rotation of the control arm $N n$ magnitudes are coded, i.e. Nn/T per second.

The possibility of associating two coding switches for transmitting a double number of items of information through the same circuits is due to the fact that the time allocated to the passage of the arm to a position of the switch is not entirely taken up in the measurement and the storage of the quantities. A dead time must be provided for the period required for the currents to be set up in the amplifiers and filters, so that the time allotted to the measurement is substantially less than $\tau/2$. It is therefore possible to utilize this dead time partially in the measurement and in the storage at a second switch, provided that an appropriate phase relation is established between the arms of the two switches.

Since the various groups of measurements must be transmitted in a particular order, it will be seen that the position of the two arms must be such that the second causes the measurement of one group at the switch I to be succeeded by the measurement of a well-defined group at the switch II, and that the measuring time at the switch II which immediately follows the measuring time at the switch I falls in the interval of the dead time succeeding the measuring time at I. It will therefore be seen that a first coarse phase adjustment must be followed by a precise adjustment.

It is the performance of these adjustments that constitutes the object of the present invention.

The device for the relative positioning of two coding switches according to the invention is characterized by the fact that it comprises two adjusting devices, namely a preliminary or rough adjustment device and a fine or precise adjustment device, the preliminary adjustment device determining a relative positioning of the two switches such that the difference from the ideal positioning is less than one switching step, and a fine adjustment device for the positioning of the two switches making it possible to alternate the coding times of the two switches with a small residual difference in relation to the regular alternation.

The preliminary adjustment device comprises a device for the adjustment of the angular position by analogue voltage incorporated in each switch and a voltage comparing device supplying a pulse at the instant when the difference between these voltages changes sign.

The preliminary adjustment comprises in a first phase the starting of the driving motor of the first coding switch

2

and then, when the difference between the stepped voltage locating the variable position of the first switch and the constant voltage locating the fixed position of the second switch is reversed, the starting of the driving motor of the second switch.

In the fine adjustment device, the position of the shafts driving the arms of the switches, which shafts carry out a half-revolution in the interval of one step, is located by means of pulses controlling logical circuits which, if the relative positions of the said pulses reflects an incorrect positioning, actuate means for slowing down the motor of the switch which is leading the other switch.

Further features of the invention will become apparent from the following description with reference to the figures of the accompanying drawings, which show by way of non-limiting example a constructional form of the apparatus according to the invention.

FIGURE 1 contains the diagrams of the distribution of the measuring times of the two associated coding switches.

FIGURE 2 is a diagram showing the phase relation between the two switches.

FIGURE 3 diagrammatically illustrates the control shafts of the two switches, with their successive positions.

FIGURE 4 is a diagram of the fine adjustment device.

FIGURE 5 diagrammatically illustrates the two networks of resistances supplying analogue voltages supplying the information regarding the positions of the two switches.

FIGURES 6 and 7 are diagrams of the signals supplied by the elements of the preliminary adjustment device.

FIGURE 8 diagrammatically illustrates a constructional form of the apparatus according to the invention.

In order to simplify the description and to enable it to be more readily understood, reference will hereinafter be made to a particular choice of T , N , n , τ , it being understood that this is only by way of example.

Each of the two switches comprises 164 positions ($N=164$) at which 9 measurements ($n=9$) are made. The time τ allocated to each position is equal to 400 milliseconds, so that the period T of the arm of the switch is equal to $164 \times 0.4 = 65.6$ seconds, during which period 1,476 measurements can be coded.

The change of position of the arm is effected by means of a rapidly operating mechanism controlled by the position of a shaft driven through a gear train (1 revolution in 800 milliseconds) by a motor rotating at a speed of 1500 r.p.m. (1 revolution in 40 milliseconds). Twice in each revolution, at intervals of 400 milliseconds, the rapidly operating mechanism causes the shaft of the switch to change position.

The curves of FIGURE 1 illustrate an ideal distribution of the measuring times of two associated coding switches. In FIGURE 1a, the notches m_1 , n_1 , m'_1 and n'_1 embrace the intervals of 400 milliseconds, each allocated to one position of the arm of the switch I. FIGURE 1b shows at p_1 , q_1 , $p'_1q'_1$, $p''_1q''_1$ the dead times during which the measurements are prevented by transient effects. The diagram of FIGURE 1c shows at x_1 , y_1 , $x'_1y'_1$, $x''_1y''_1$ the times utilized by the measurement and the storage.

The diagrams of FIGURES 1d, 1e and 1f correspond to the preceding diagrams in the case of the switch II. There are marked in FIGURE 1f two measuring periods x_2y_2 , $x'_2y'_2$ at successive positions, represented in the ideal position in which they are staggered by 200 milliseconds in relation to those of the switch I.

Referring to FIGURE 1g, the instant t_0 and 0_1 midway in two successive switching intervals of the switch I and of the 40-millisecond zones centered on t_0 and 0_1 h_0k_0 and h_1k_1 , a satisfactory phase relation will be obtained for

the separation of the measurements if the switching instants m_2 and n_2 are situated within the said zones. However, owing to the necessity for a fixed order of succession in the measurements obtained at the two switches, it is necessary that, if the switching interval m_1n_1 is allocated to a particular position, for example the position 164, at the switch I, the interval m_2n_2 should be allocated to the corresponding position at the switch II, and a pulse supplied at the instant t_2 when the arm of the switch II leaves the position 164 at n_2 must therefore be located in the interval h_1k_1 . Under these conditions, 2952 measurements can be coded in 65.6 seconds.

If t_0 is the instant 800 milliseconds after t_0 and if a preliminary adjustment has limited to less than ± 400 milliseconds the maximum possible difference between the actual position of the arm of the second switch and its ideal position, it is ensured that the instant t_2 will necessarily be located in the interval $t_0t'_0$. Let A (FIGURE 2) be the 380-millisecond zone t_0h_1 , C the 380-millisecond zone $k_1t'_0$, and B the central 40-millisecond interval h_1k_1 . The phase relation will be correct and the switches will be synchronised as long as t_2 is located in zone B. If t_2 is in the zone A, it will be said that the switch I is leading the switch II, and if it is in the zone C, it will be said that it is lagging.

According to the invention, the instants t_0 , t'_0 and the zones B associated with the instant θ_1 , commencing at the time $t_1=\theta-20$ ms., which elements make possible a defining the phase relation between the two switches, are located by the following means.

It has been stated in the foregoing that the shafts determining the step-by-step rotation of the arm of each of the switches carry out one rotation in 800 milliseconds and start by means of a cam-operated mechanism the progress of the arm of the switch into two opposite positions at the instant of the entry into the zones centered on J_1 and J'_1 or J_2 and J'_2 of a reference diameter of the said shafts (FIGURE 3).

For the shaft associated with the switch I (FIGURE 3₁), the position J_1 corresponds successively to m_1 , m'_1 . . . , the position J'_1 to n_1 , n'_1 , and so on.

The instants t_0 , t'_0 are defined by the entry of the reference diameter into the position T_0 offset in relation to J_1 by $\pi/2$ in the direction of rotation indicated by the arrow (instant later by 200 milliseconds than that of m_1), the instants t_1 , $t'_1=t_1+800$ ms. being defined by the entry of the same diameter into the position T_1 offset in relation to T_0 by $\pi \times 380/400$, i.e. $19\pi/20$.

Pulses are supplied at the instants t_0 , t'_0 , t_1 . . . by means of which an example will hereinafter be given, and the zone B is characterised by the change of state of a monostable trigger circuit when it receives the pulse at its input at the time t_1 , and its return to its prior state 40 milliseconds later.

For the second switch (FIGURE 3₂), in which the passage of a reference diameter through J_2 and J'_2 corresponds to the switching instants m_2 , m'_2 of FIGURE 1d, the instant t_2 will be defined by the passage of the reference diameter through the position J'_2 .

In order to retain or to restore the correct phase relation between the two switches, the invention provides members by means of which, in accordance with the position of the pulse t_2 of the second switch in relation to the intervals A, B, C, defined by the first, it is possible to determine the reduction of the speed of the motor controlling the progress of one or other of the two switches, of the switch II in the zone A and of the switch I in the zone C, or to exert no action in the zone B.

These speed reducing actions are controlled by the state of binary flip-flops BBZ₁, BBZ₂ (FIGURE 4) associated respectively with the members adjusting the speed of the two motors, and of which the inputs receive, at the time of the pulse supplied at the time t_2 , signals depending upon the position of the said pulse. The posting of the signal 1 at one of the outputs, for example the zero output,

determines the speed reduction of the first or second motor respectively.

The logical circuits by means of which this result can be obtained are illustrated in FIGURE 4. They comprise two logical OR circuits and four logical AND circuits comprising diodes of known type. A₀, A₁, A₂ represent amplifiers receiving at their inputs the pulses supplied at the times t_0 , t_1 , t_2 respectively. BB₁ is a bistable flip-flop whose inputs are connected to the outputs of A₀, A₁. The binary signals set up at the outputs of the said flip-flop will be denoted by a and $\bar{a}$ respectively.

Depending upon the zones, they take the following values:

15 Zone A: $a=1$, $\bar{a}=0$
Zones B and C: $a=0$, $\bar{a}=1$

BM₁ is a flip-flop to the input of which the signal $\bar{a}$ is applied. The negative pulse registered by the signal at the instant t_1 changes the normal state of the flip-flop for a period equal to 40 milliseconds, that of the interval B. In the zone B, b being the output signal of BM₁, we have $b=1$, while in the other zones we have $b=0$.

The output of the amplifier A₂ is connected to the input of a monostable flip-flop BM₂ whose output signal C represents the value 1 only at the instant t_2 of the pulse.

The logical OR circuit and the inverting circuit In supply the output signals representing $(a+b)$ and $(\bar{a}+\bar{b})$ respectively, while the circuits ET₁, ET₂, ET₃, ET₄ supply the output signals ac , $\bar{a}\bar{c}$, $c(a+b)$, $c(\bar{a}+\bar{b})$ respectively. The bistable flip-flop BBZ₁ receives at its input 0 the signal $c(a+b)$ and at its input 1 the signal $c(\bar{a}+\bar{b})$. The bistable flip-flop BBZ₂ receives at its input 0 the signal $\bar{a}\bar{c}$ and at its input 1 the signal ac .

30 It will thus be seen that there are received at the two terminals of each of the binary flip-flops at the instants of the pulses (t_2) signals which always represent opposite binary digits, of which only one is consequently effective.

In the zone B, $\bar{a}\bar{c}$ and $c(a+b)$ represent 1. The effect 40 of the signal 1 at the zero input terminals is to apply the zero signal to the output terminals 0 of the two flip-flops. Therefore, no retarding action is exerted on the motors, and this is appropriate for maintaining a correct position.

In the zone A, $ca=1$, which gives a signal 1 at the 45 output 0 of BBZ₂, and the speed reduction of the second motor is thus obtained. On the other hand, since $c(a+b)$ remains equal to 1, no action is exerted on the first motor.

In the zone C, $\bar{a}+\bar{b}$ represents the binary digit 1, which 50 is set up at the output 0 of BBZ₁, which results in a reduction of the speed of the first motor, while since $\bar{a}\bar{c}$ is equal to 1, no action is exerted on the second motor.

The desired effects can thus in fact be obtained by 55 means of the described logical circuits. There will now be described the principle of the operating device for effecting the preliminary (so-called rough) adjustment at the starting of the motors, which is rendered inoperative when a sufficiently small phase difference has been set up, and the fine adjustment device is then substituted therefor.

The principle applied is as follows: At the starting of the motors, the motor associated with the switch I is fed with full power, while the second motor is not fed. The 60 164 positions of the switch are characterised by voltages varying linearly from the position 1 to the position 164. The arm of the switch II is then stationary and indicates a fixed constant voltage corresponding to its position. The arm of the switch I indicates a stepped voltage. At the instant when these voltages are equal, the switch II is set in operation by a comparing device.

The precise adjustment device is placed in circuit only 65 about 1 second after the starting of the second motor so as to enable the latter to reach its full speed.

There will now be given a number of examples of the manner in which the precise adjustment and the preliminary adjustment are carried out.

5

For the precise adjustment, the pulses employed for bringing the arms of the switches into phase are obtained by the travel of a magnetic arm, conforming to the position of the cam-operated mechanism past magnetic heads disposed in the positions marked T_0 and T_1 in FIGURE 3₁ in the case of the first switch, and in the position marked J_2 in FIGURE 3₂ in the case of the second switch.

With regard to the means for reducing the speed of the motors, they depend upon the type of motors employed.

In a preferred construction, the motors are of the synchronized asynchronous type. Having ample dimensions, these motors remain in step once the synchronization has been effected. In order to obtain the synchronization, the slip of the motor which is to be slowed down is effected by reducing its feed current by the insertion of a set of resistances in series in each phase, which produces the out-of-step condition.

The outputs of the flip-flops BBZ₁, BBZ₂ are connected to the windings of two relays which control switches which effect the series connection of resistances in the feed wires of the motors associated with the switches 1 and 2 respectively.

The preliminary adjustment circuit will now be described with reference to FIGURE 5 et seq.:

FIGURE 5 shows the two networks of 163 identical resistances R supplying analogue voltages giving the information regarding the positions of the two switches. These two networks are fed by a common source (of 24 volts in the example given) and the same current flows therethrough.

Resistances r_1 and r_2 are connected to the two networks on the side of the 24-volt terminal, bringing to about 8 volts the voltage difference across the terminals of the networks, while a resistance R/2 is disposed between the terminal 0 and the input of the second network.

The voltage difference between two successive positions is $\frac{8}{163}$ volts at the two networks, but owing to the additional resistance R/2 the corresponding voltage levels in the two switches are staggered by a half-step (upwards at the second).

FIGURE 6 shows at 6a the stepped signals obtained in the case of switches having only four positions in the case of the ideal staggering of the arms.

These signals are applied to the input of a differential amplifier AD (FIGURE 8), the voltage curve at the output of which is that illustrated in FIGURE 6b, which comprises 200-millisecond crenulations at regular intervals except at the instant of the return to zero of the analogue voltages which corresponds to a void.

There are shown at 6c the positive pulses which are set up at the flip-flop input connected to the output of the differential amplifier AD, which flip-flop is sensitive only to positive pulses. These pulses are spaced apart by 400 milliseconds, except at the return of the analogue voltages through zero, where a spacing of 800 milliseconds is observed.

This result is not confined to the example of FIGURE 6, and is obtainable regardless of the number of positions of the switch.

There will be seen in FIGURE 7 at 7a and 7b the modification resulting in the case of these curves from a backward shift of 800 milliseconds of the second switch in relation to its ideal position.

There will be seen at 7c the corresponding positive pulses, whose repetition time is equal to the period of the switches, which is a general result.

FIGURE 8 illustrates the whole apparatus according to the invention in its preferred form.

MC₁, MC₂ represent the two switching motor sets. The first motor is fed by the poles 1, 2, 3 from a three-phase voltage source at its terminals 11, 12, 13. The second motor is fed at 31, 32, 33 at the downstream terminals of a general contactor S₁.

The terminals of the assembly MC₁ at which there are set up at the times t_0 and t_1 the pulses utilised in the pre-

6

cise adjustment are designated 4 and 5, 6 is the terminal of MC₂ at which the pulse is supplied at the time t_2 , and 7 and 8 are the terminals of MC₁ and MC₂ at which the analogue voltages giving the position information are set up.

The fine adjustment device illustrated in FIGURE 4 is designated 9, of which the outputs 10 and 20 are the output terminals 0 of the flip-flops BBZ₁, BBZ₂, which are connected to the negative pole of the feed battery through the windings of relays 14 and 24 which, when their contacts are in the operating position, place the windings of speed reducing contactors 15 and 25 respectively on open circuit between 32 and 33, thus bringing about the insertion of speed reducing resistances 16 and 26 connected to the contact terminals of the contactors 15 and 25 respectively.

The closing of the contactor S₁ by the starting button M, which contactor remains self-energized, ensures feeding of the first motor and, owing to earthing of the zero input of the flip-flop BB₂ at 27, brings about the establishment at the output 1 of BB₂ of a zero voltage, the energization of the relay 30 connected between the said output and the negative pole of the feed source and consequently the breaking by means of a contactor S₂ of the feed circuits of the second motor, which remains inoperative.

At the same time, earth applied to a terminal 34 of the precise adjustment device brings the flip-flops BBZ₁, BBZ₂ of the fine adjustment device (FIGURE 4) into the position in which the relay 14 and 24 are inoperative, which results in short-circuiting of the speed reducing resistances 16 and 26.

The terminals 7 and 8 of the motor-switches MC₁ and MC₂ are connected respectively to the input terminals 7 and 8 of a differential amplifier AD. When the analogue voltages at the input terminals of the differential amplifier AD become equal, the crenulated curve 6b represents a discontinuity, and a pulse is set up at the output 29 of the differential amplifier AD, which pulse, applied to the input 1 of the flip-flop BB₂, changes its state if it is positive (FIGURE 6) and produces the return of the contact of the relay 30 to the inoperative position. The control circuit of the contactor S₂ is then closed and remains self-energized, and the second switch motor MC₂ is started. At the same time, earth is disconnected from 34, whereby the fine adjustment circuit 9 is released. The operation of this circuit may delay the bringing of the motors to their normal speed, and a resistance-capacitance delay device is therefore provided, which has a time constant of about 1 second.

The correct synchronization of the switch motors MC₁, MC₂ is indicated by the extinction of a red pilot light R and the ignition of a green pilot light V. For this purpose, a bistable flip-flop BB₃ receives at its input terminal 1 the pulses (t_2) about every 800 milliseconds, while its input terminal 0 is connected to the output 29 of the differential amplifier AD. The output 0 of the flip-flop BB₃ is connected to the negative feed pole through a delay device 35 and a relay winding 36 whose contact feeds in its inoperative position a green pilot light V and in its operative position a red pilot light R.

A positive pulse (t_2) applied to the input 1 of the flip-flop BB₃ has the effect of causing a voltage in the neighbourhood of zero to be set up at the output 0 of BB₃, which results in feeding of the winding 36 and causes ignition of the red pilot light R, while a positive pulse applied to the input 0, coming from 29, changes the state of the flip-flop BB₃, and causes a negative voltage to be set up at the output 0 of BB₃ and consequently the release of the relay 36 and the ignition of the green pilot light V.

Now, it has been seen that the pulse (t_2) occurs at the instant when the rapidly operating mechanism of the second switch commences to operate. Therefore, t_2 precedes the change of position of the second switch by a period which may vary from 5 to 25 milliseconds depending upon

the accuracy of the mechanism. In the case of correct synchronism of the switch motors MC_1 and MC_2 (FIGURE 6), the pulse (t_2) is therefore always succeeded by a pulse emanating from the output of the amplifier AD at a time interval not exceeding 25 milliseconds (FIGURE 6d). The delay device 35 prevents the response of the relay 36 during this interval, so that the green pilot light remains continuously alight.

In the event of incorrect synchronism, on the other hand, the positive pulses at the input 0 of BB_3 are set up only once per period of the switches, which period is equal to 65.6 seconds in the case of 164 positions, and it will be seen (FIGURE 7d) that the state of the flip-flop will generally be fixed by the pulses (t_2), the positive pulses at the output AD being capable of producing the ignition of the green pilot light only for a period obviously shorter than 800 milliseconds.

When an incorrect synchronism is observed, the general stop button A is operated and the operations are recommenced. This, however, is exceptional and can occur only as a result of disturbing currents at the input of the amplifier AD .

On the other hand, the contacts 37 and 38 supplied by the speed reducing contactors 15 and 25 during the precise adjustment determine the ignition of an orange pilot light OR , which thus indicates the adjustment periods.

What is claimed is:

1. Apparatus for the synchronization and relative positioning of two coding switch means, comprising:

two separately controllable switch driving means effectively providing a plurality of switching steps with the coding times thereof alternating,

two adjusting means including a preliminary adjusting means operatively connected to said switch means and driving means, and a fine-adjusting means for controlling the fine adjustment of the positioning of the two switch means to enable the coding times of the two switch means to alternate with a slight residual difference in relation to the regular alternation thereof,

said preliminary adjusting means for determining a relative positioning of the two switch means such that the difference from the ideal positioning thereof is smaller than one switching step,

said preliminary adjusting means further including switch position-locating means operable by analogue voltage and voltage comparing means operatively connected with said driving means.

2. Apparatus according to claim 1, wherein said preliminary adjusting means includes locating means operable by an analogue voltage incorporated in each switch means for locating the angular position thereof and voltage-comparing means operable to supply a pulse at the instant of change in sign in the difference between these voltages, each switch driving means including an electric driving motor, said preliminary adjusting means further including first means operable in a first phase for starting the driving motor of one of the coding switch means, and second means operable in a second phase for starting the driving motor of the other coding switch means upon reversal of the difference between the stepped voltage locating the variable position of said one switch means and the constant voltage locating the other switch means.

3. Apparatus according to claim 2, further comprising speed-reducing means including a speed-reducing contactor for each driving motor, control windings for the speed-reducing contactors, and relay means controlled by said fine-adjusting means and operatively connected with said control windings.

4. Apparatus according to claim 2, wherein said voltage comparing means includes a differential amplifier to the input of which are applied the analogue voltages, flip-flop means operatively connected to the output of said differential amplifier, and relay means controlled by said

flip-flop means and operable to control the contactor of the motor for the other coding switch means.

5. Apparatus according to claim 2, wherein speed-reducing means are operatively associated with the driving motor of each switch means and each switch means has a driving shaft for driving a respective switch arm, said shafts carrying out a half-revolution in the interval of one step, and locating means in said fine-adjusting means for locating the position of said shafts including pulse-producing means for producing pulses of which the relative position reflects the position of the switch means and logical circuit means operatively connected with said pulse-producing means and operable to actuate, in response to a relative position of said pulses reflecting an incorrect positioning, the speed-reducing means of the motor driving the then leading switch means.

6. Apparatus according to claim 5, wherein said logical circuit means include binary flip-flop means having inputs and outputs, said outputs being operatively connected with said speed-reducing means, and means operatively connecting said pulse-producing means with said inputs to apply to said inputs at the instant of the reference position pulse supplied by the other switch means, signals depending upon the position of the said last-mentioned pulse.

7. Apparatus according to claim 6, further comprising a synchronism indicator including indicating pilot lamp means, a relay for controlling said lamp means, a bi-stable flip-flop device which receives the reference pulses of the other coding switch means and is operatively connected to the output of said differential amplifier, and a delay device operatively connecting said bi-stable flip-flop device with said relay.

8. Apparatus according to claim 1, wherein speed-reducing means are operatively associated with each driving means including a motor and each switch means has a driving shaft for driving a respective switch arm, said shafts carrying out a half-revolution in the interval of one step, and locating means in said fine-adjusting means for locating the position of said shafts including pulse-producing means for producing pulses of which the relative position reflects the position of the switch means and logical circuit means operatively connected with said pulse-producing means and operable to actuate, in response to a relative position of said pulses reflecting an incorrect positioning, the speed-reducing means of the motor driving the then leading switch means.

9. Apparatus according to claim 8, wherein said logical circuit means include binary flip-flop means having inputs and outputs, said outputs being operatively connected with said speed-reducing means, and means operatively connecting said pulse-producing means with said inputs operable to apply to said inputs, at the instant of the reference position pulse of the other switch means supplied by said pulse-producing means, signals depending upon the position in time of each reference position pulse.

10. Apparatus according to claim 9, wherein said speed-reducing means includes a speed-reducing contactor for each driving motor, control windings for the speed-reducing contactors, and relay means controlled by said fine-adjusting means and operatively connected with said control windings.

11. Apparatus according to claim 1, comprising means for producing reference position pulses for each of said switch means, and wherein said fine adjusting means includes a bi-stable flip-flop means having input and output means, the reference position pulses of one switch means being applied to the input means of said bi-stable flip-flop means, a monostable flip-flop means having input and output means, the reference position pulses of the other switch means being applied to the input means of said monostable flip-flop means, logical circuit means with the inputs thereof connected to said output means for combining in the outputs thereof the signals supplied thereto, and two bi-stable flip-flop means receiving in the

inputs thereof the combination of signals from said logical circuit means and each supplying a current for the control of the contactors for the reduction of the speed of the driving motors for said coding switch means.

12. Apparatus according to claim 4, further comprising a synchronism indicator including indicating pilot lamp means, a relay for controlling said lamp means, a bi-stable flip-flop device which receives the reference pulses of the other coding switch means and is operatively connected to the output of said differential amplifier, and a delay device operatively connecting said bi-stable flip-flop device with said relay. 10

13. Apparatus for the synchronization and relative positioning of two coding switches, comprising two coding switch means effectively providing a plurality of switching steps with the coding times thereof alternating, two adjusting means operatively connected with said two coding switch means including preliminary adjusting means for determining a relative position of the two switch means such that the difference from the ideal positioning thereof is smaller than one switching step, and fine-adjusting 15

5

means provided with logical circuit means for controlling the fine adjustment of the positioning of the two coding switch means in response to the relative position of reference pulses indicative of the position of said coding switch means, said reference pulses being applied to said logical circuit means to enable the coding times of the two switch means to alternate with a slight residual difference in relation to the regular alternation thereof.
